UNITED STATES PATENT OFFICE.

EDMOND RAGONOT, OF MALAKOFF, FRANCE.

VACUUM CLEANER.

Application filed March 7, 1925, Serial No. 13,685, and in France March 19, 1924.

This invention has for its object means by which the distance from the ground of the suction inlet or nozzle of an electrically driven vacuum cleaner mounted upon rollers or wheels can be rapidly and easily adjusted.

The provision of such an adjustment is necessary for obtaining high efficiency, as the height of the suction inlet above the ground should vary according to the nature thereof, for example, for parquet flooring or a carpet, and if a carpet, for a thick nap carpet or short nap carpet.

Such an adjustment has often been made by raising the rear roller of the apparatus. This method, however, is slow and does not allow sufficient adjustment and is hardly applicable when the apparatus is provided with a rear self steerable wheel, which is moved about a vertical axis.

According to this invention the adjustment is effected on the front wheels by mounting these in a vertically adjustable pivoted frame. The frame is caused by a spring to bear against a cam which can be moved relatively to the body of the apparatus.

The invention is illustrated in the accompanying drawings, of which Figure 1 is a sectional elevation of the apparatus, Figure 2 is a partial section on the line A B C of Figure 1, and Figure 3 shows details of the cam.

The body portion of the apparatus includes the casing 1 and the suction inlet 2, mounted upon the rear self-steering wheel 3 and the front wheels 4, 4, mounted upon an axle 5 carried by a frame 6 movable about pivots 7, 7, positioned adjacent the rear of the suction inlet.

The cylindrical portion 8 of the apparatus, forming a connection between the suction inlet 2 and the casing 1, is embraced by a cam 9 cut from a relatively thin and flexible sheet metal piece distorted by being bent slightly out of shape before being mounted on the cylindrical portion 8, so that it is by its elasticity firmly maintained in position in the cylindrical portion and will not become displaced when the apparatus receives a shock. A floating cam 9 of the type herein disclosed does not require any external locking mechanism for holding the same in position, the resiliency thereof and the manner in which it is mounted serving to prevent displacement thereof.

Cam 9 is provided with a handle 10 by which it can be turned in its housing 8 and so brought into any desired position between the two extreme positions determined by the abutment 11 or 12 coming against a fixed pin 13. 15 is an angle piece fixed to the free end of frame 6 and which is firmly pressed against the cam 9 by blade springs 14, 14.

In order instantaneously to adjust the height of the suction inlet above the ground it is only necessary to make a suitable movement of the handle 10 and owing to the elasticity of the cam 9 any regulation made is frictionally maintained, no stop or locking device being required.

Handle 10 can be manipulated conveniently by one hand to adjust the height of the suction inlet.

What I claim is:—

1. In an electrically operated vacuum cleaner, the combination with a wheel supported body casing and a suction inlet portion, of a frame pivoted to said suction inlet portion for vertical movement relatively thereto and carrying wheels, means comprising a cylindrical member connecting said body casing and suction inlet portion together and a cam embracing said cylindrical member and acting on said frame for controlling the position thereof.

2. In an electrically operated vacuum cleaner, the combination with a body portion mounted on wheels and including a suction inlet portion, of a frame pivoted to said suction inlet portion for vertical movement relatively thereto and carrying a supporting wheel, a circular guide formed on said body portion, a cam slidably carried by said guide and acting on the frame to adjust the latter vertically and cooperating stop elements carried by said body portion and said cam for limiting the movement of the cam.

3. The combination in an electrically operated vacuum cleaner provided with a body portion including a suction passage extending therethrough, of a wheel carrying frame pivotally secured to said body portion, a cam member rotatably mounted upon said body portion and encircling said suction passage, said cam member having a cam surface engaging said wheel carrying frame for raising or lowering the latter, and means for rotating said cam.

4. In an electrically operated vacuum cleaner, the combination with a body por-

tion mounted on wheels, of a frame pivotally connected to said body portion for vertical movement relatively thereto and carrying a supporting wheel, said body portion including a supporting groove, a cam mounted within said groove and frictionally engaging the same and formed with a cam sur-

face engaging said frame for controlling the vertical position of the latter, the friction between said cam and groove assisting in ¹⁰ preventing displacement of said cam.

In testimony whereof I affix my signature.

EDMOND RAGONOT.
